UNITED STATES PATENT OFFICE.

BENJAMIN P. RUCKER, OF WILKINSBURG, PENNSYLVANIA, ASSIGNOR TO
WESTINGHOUSE ELECTRIC & MANUFACTURING COMPANY, A CORPOR-
ATION OF PENNSYLVANIA.

CIRCUIT-BREAKER.

No. 856,425.

Specification of Letters Patent.

Patented June 11, 1907.

Application filed September 22, 1904. Serial No. 225,481.

To all whom it may concern:

Be it known that I, BENJAMIN P. RUCKER, a citizen of the United States, and a resident of Wilkinsburg, in the county of Allegheny and State of Pennsylvania, have invented a new and useful Improvement in Circuit-Breakers, of which the following is a specification.

My invention relates to overload interrupting devices for electric circuits, and it has for its object to provide a circuit-breaker of simple and inexpensive construction, which shall be compact in arrangement and effective for low capacity service.

In the accompanying drawings, illustrating my invention, Figure 1 is a front elevation, Fig. 2 a central, longitudinal section and Fig. 3 an end view, looking upward, of a switchboard instrument embodying its essential features.

Referring now to the structural features illustrated, 1 is a base-plate of suitable non-conducting material, such as marble, slate or porcelain, which may be a switchboard panel.

As here indicated, the plate 1 is provided with three recesses 2, 3 and 4 in its rear face, the recess 2 containing the nuts and washers 5 and 6 of two binding screw-bolts 7 and 8. Clamped beneath the head of the screw-bolt

7, is a terminal piece 9, and between this terminal and the face of the plate is clamped a metal strip or plate 10, a portion of which is bent at substantially right-angles to the body part and is provided, at its outer end, with a contact terminal block 11 of carbon or other substantially infusible conducting material, the front face of the block 11 being preferably concave, as indicated.

The lower end of the plate 10 is provided with extensions 12 that also project substantially at right-angles to the face of the slab 1 and their outer ends are bent backward upon themselves so as to form concave jaws between which a movable contact terminal may be readily inserted. An angular stop piece 13 and one end of a spring locking arm 14 are clamped between the head of the screw-bolt 8 and the outer face of the plate 10.

Adjacent to the other or lower end of the slab 1, is located a sheet metal plate 15 that is clamped to the face of the slab by means of two screw-bolts 16 and 17, the nuts and wash-

ers 18 and 19 of these screw-bolts being located respectively in the recesses 3 and 4. A terminal piece 20 is clamped between the head of the bolt 16 and the outer face of the plate 15, as indicated in Fig. 2. The plate 15 is provided, at its lower end, with two bracket arms 21 that project at right-angles to the body portion of the plate and are provided, adjacent to their outer ends, with bearings for a rod or short shaft 22. Journaled upon the rod or shaft 22 and just inside the bracket arms 21, are two arms 23 which project from a cylinder or ferrule 24 of suitable conducting material, the function of which, and also the relation to other parts of the device, will be hereinafter more fully described.

The outer ends of the arms 23 are bent inward substantially at right-angles to the body portion, as indicated at 25. Each of the brackets 21 is cut, adjacent to the base-plate 15, to form a tongue 26 that is bent substantially at right-angles to the body portion in order to constitute stops for the sides of the U-shaped portion 27^a of a coil-spring 27, the outer ends 27^b of which project downwardly and bear upon the bent ends 25 of the arms 23.

By means of the construction and arrangement here shown, the spring 27 serves both as a means for effecting a rapid opening movement of the movable member of the circuit-breaker when an overload occurs and as a cushion or buffer for said movable member when it reaches the limit of its opening movement. The plate 15 is also provided with integral projections 28 that extend substantially at right-angles to the base portion and are bent backward upon themselves to form spring contact arms the outer ends of which may be split for the purpose of making more intimate contact with the cylinder 24, as indicated in Fig. 1.

Rigidly mounted in the cylinder 24, is one end of a tube 29, preferably of some suitable non-conducting material, and surrounding the other end of this tube, is a cylinder or ferrule 30 of good conducting material and of such diameter as to pass between and make contact with the spring contact arms 12 which project from the plate 10. In the outer end of the cylinder or ferrule 30, is

mounted a block 31 of carbon, or other substantially infusible conducting material, having a convex end face of such curvature as to accurately fit the concave face of the block 11.

5 Fitted within the tube 29, is an iron tube 32 and within this tube is rigidly mounted a head 33, also of magnetizable material. This head has a central bore 34 and adjacent thereto is provided with a locking pin 35 that 10 normally projects through a hole in the spring catch 14 and thus locks the movable member of the breaker in closed position.

In order to close the breaker, I provide a handle or knob 36, which is rigidly connected 15 to the parts 29, 32 and 33 by means of a projecting pin 37. The head 33 is provided with a downward or rearward cylindrical extension 38 of relatively small diameter, and rigidly mounted upon this extension is a tube 39 20 that projects beyond the outer or lower end of the ferrule 24 and is provided, on its outer side, with a slot 40. Located between the tubes 32 and 39, is a helical coil 41, one end of which is connected to the ferrule 30 and 25 the other end to the ferrule 24, so that the coil is always in series relation between the terminal pieces 9 and 20 of the instrument when the breaker is closed.

Loosely mounted within the tube 39, is a 30 movable, magnetizable core 42 having a pin 43 of non-magnetizable material the free end of which projects into the bore or passage 34 in the head 33. The outer or lower end of the core 42 is provided with a cylindrical recess 44, into which projects a screw 45. The outer end of the screw is provided with an adjusting nut 46 and within the tube 39 is located a disk 47 that is threaded upon the screw 45 and is provided with a projection 48 40 that is located in the slot 40 in order to prevent rotation. By means of these devices, the position of the core 42 may be so adjusted within the magnetic field produced by the coil 41 as to insure operation of the breaker 45 at any predetermined degree of overload, within the capacity of the device. When the current in the circuit which contains the coil 41 exceeds the predetermined limit for which the breaker is set, the core 42 will be lifted 50 and the pin 43 with which it is provided will be projected against the outer end of the spring catch 14 and thus remove it from the locking pin 35. As soon as this result is effected, the spring 27, which is held under torsional strain so long as the breaker is closed, 55 will serve to open the breaker.

It will be understood, from the illustration and foregoing description, that the circuit-breaker embodying my invention is of simple 60 and compact construction, and since the metal parts of the device are stamped or otherwise formed from sheet material, the construction is inexpensive and, at the same time, correspondingly light and well adapted

to the small capacities for which the instrument is designed.

I claim as my invention:

1. In a circuit-breaker, the combination with a base and stationary contact terminal jaws projecting laterally therefrom, of a movable member mounted to operate in a plane perpendicular to said base and comprising an insulating body portion, and terminal pieces surrounding the ends thereof to engage the terminal jaws, means for locking said member in closed-circuit position, means for releasing said member when the current carried by it exceeds a predetermined limit, and means for throwing the member to open-circuit position when released. 75

2. In a circuit-breaker, the combination with stationary contact terminals, of a pivotally mounted member comprising an insulating tube, terminal bands surrounding said tube and a tripping coil electrically connecting said terminal bands. 80

3. In a circuit-breaker, the combination with two pairs of contact terminal jaws, of a pivotally mounted member comprising an insulating body portion and electrically connected terminal pieces surrounding the ends thereof in position to engage the respective pairs of jaws, means for locking said member in closed-circuit position, means for releasing said member when the current carried by it exceeds a predetermined limit and means for throwing the member to open-circuit position when released. 90

4. In a circuit-breaker, the combination with stationary contact terminals, of a pivotally mounted member comprising an insulating tube, terminal bands mounted on said tube, a tripping coil connecting said terminal bands, and stationary and movable iron cores for said tripping coil. 100

5. In a circuit-breaker, the combination with stationary contact terminals, of a pivotally mounted member comprising an insulating tube, terminal bands mounted thereon, a tripping coil electrically connecting said terminal bands, stationary and movable iron cores and means for adjusting the air gap between the said cores. 110

6. In a circuit-breaker, the combination with stationary contact terminal jaws, of a pivotally mounted member comprising an insulating portion and electrically connected ferrules on the ends thereof, means for locking said member in closed-circuit position, means for releasing said member when the current carried by it exceeds a predetermined limit and means for throwing the member to open-circuit position when released. 115

7. In a circuit-breaker, the combination with stationary contact terminal jaws, of a pivotally mounted member comprising an insulating body portion and electrically con-

- 5 nected ferrules adapted to engage the said stationary terminal jaws, means for locking said member in closed-circuit position, means for releasing said member when the current carried by it exceeds a predetermined limit and means for throwing the member to open-circuit position when released.
- 10 8. In a circuit-breaker, the combination with stationary contact terminal jaws, of a pivotally mounted member comprising an insulating body portion, and electrically connected terminal ferrules mounted thereon and adapted to engage the said stationary terminal jaws, means for locking said member in closed-circuit position, means for releasing said member when the current carried by it exceeds a predetermined limit and means for throwing the member to open-circuit position when released.
- 15 15 9. In a circuit-breaker, the combination with stationary contact terminals, of a pivotally mounted member comprising an insulating tube and electrically connected ferrules therefor, means for locking said member in closed-circuit position, means for releasing said member when the current carried by it exceeds a predetermined limit and means for throwing the member to open-circuit position when released.
- 20 20 10. In a circuit-breaker, the combination with stationary contact terminals, of a pivotally mounted member comprising an insulating tube and electrically connected terminal pieces mounted thereon, means for locking said member in closed-circuit position, means for releasing said member when the current carried by it exceeds a predetermined limit and means for throwing the member to open-circuit position when released.
- 25 35 11. In a circuit-breaker, the combination with stationary contact terminals, of a pivotally mounted member comprising an insulating tube, terminal pieces mounted thereon and a helical coil electrically connecting said terminal pieces.
- 30 45 12. In a circuit-breaker, the combination with stationary contact terminals, of a pivotally mounted member comprising an insulating tube, terminal pieces mounted thereon and a helical coil within the tube and electrically connecting the said terminal pieces.
- 40 50 13. In a circuit-breaker, the combination with stationary contact terminals, of a pivotally mounted member comprising an insulating tube, conducting ferrules therefor which are adapted to engage the stationary contact terminals and a helical coil within the insulating tube which electrically connects the said ferrules.
- 55 60 14. In a circuit-breaker, the combination with stationary contact terminal jaws, of a pivotally mounted, tubular member comprising an insulating body portion and contact terminal bands which are electrically connected by means of the circuit-breaker tripping coil and are adapted to engage said jaws.
- 65 15. In a circuit-breaker, the combination with stationary contact terminals, of a pivotally mounted, tubular member comprising an insulating portion, contact terminal bands mounted thereon which are adapted to engage the stationary contact terminals and which are electrically connected by means of the circuit-breaker tripping coil.
- 70 16. In a circuit-breaker, the combination with a base having stationary contact terminals, of a spring arm projecting outwardly from the base, a tubular movable member provided with contact ferrules and with a locking pin to be engaged by said spring arm, and having a longitudinally-movable core provided with a tripping rod to engage the outer end of the spring arm and deflect it from the locking pin.
- 75 17. In a circuit-breaker, the combination with stationary contact terminals, of a spring catch, a pivotally mounted, tubular member, external contact bands and a locking pin which is adapted to engage the said spring catch, an internal coil, stationary and movable iron cores therefor and means connected with the movable iron core for disengaging the said spring catch from the said locking pin.
- 80 18. The combination with a solenoid and its core, of a calibrating tube into which the core is adapted to pass, an adjustable stop located in said tube, and adjusting means for said stop extending below said tube a distance constant for all adjustments of said stop.
- 85 19. The combination with a solenoid and its core, of a calibrating device comprising a stop and operating means therefor free from movement in the direction of said core.
- 90 20. The combination with a solenoid and its core, of a calibrating tube into which the core is adapted to pass, a stop for said core in said tube, and means for moving said stop, said means having a longitudinal fixed position relative to said tube.
- 95 21. An electric switch having means for controlling it comprising a solenoid including a winding, a hollow core in the solenoid, a slotted tubular projection having a screw mounted to operate therein, and a nut within the tubular projection and provided with a part fitting in the slot of said tubular projection for preventing the nut from turning when the screw is rotated to adjust the position of the nut which forms a limiting stop for the core of the solenoid, substantially as described.
- 100 22. An electric switch having means for

actuating it, comprising a solenoid including a winding, a slotted guide, an adjusting screw mounted in the guide, a nut on the screw and a tubular, reciprocating core cooperating with the nut in the guide and excitable by the winding to actuate the switch, substantially as described.

In testimony whereof, I have hereunto subscribed my name this 21st day of September, 1904.

BENJAMIN P. RUCKER.
